UNITED STATES PATENT OFFICE.

HARRY ALBERT WALKER, OF SAN ANTONIO, TEXAS.

COMBINED TIRE GAUGE AND ENGINE COMPRESSION GAUGE.

Application filed September 20, 1920. Serial No. 411,464.

To all whom it may concern:

Be it known that I, HARRY ALBERT WALKER, a citizen of the United States, and a resident of San Antonio, in the county of Bexar and State of Texas, have invented a new and useful Improvement in Combined Tire Gauges and Engine Compression Gauges, of which the following is a full, clear, and exact description.

10 My invention relates to improvements in combined tire gauges and engine compression gauges, and it consists in the combinations, constructions and arrangements herein described and claimed.

15 An object of my invention is to provide a gauge which will accurately indicate the compression in a pneumatic tire, or the compression obtained in an engine cylinder, and in which the indicating stem is held positively in any position to which it has been moved by pressure, so that it may be read at leisure.

20 A further object of my invention is to provide a device of the type described in which the indicating stem may be readily released from its position and restored to its normal position.

25 A further object of my invention is to provide a device which is positive in action, and which is not liable to easily get out of order.

30 Other objects and advantages will appear in the following specification, and the novel features of the invention will be particularly 35 pointed out in the appended claims.

35 My invention is illustrated in the accompanying drawings, forming part of this application, in which—

40 Figure 1 is a longitudinal sectional view of the device,

45 Figure 2 is an enlarged sectional view of a portion of the device.

50 Figure 3 is a side view of the device as applied to an engine cylinder, and

55 Figure 4 is a section along the line 4—4 of Figure 1.

60 In carrying out my invention, I provide a base portion 1 which is in the nature of a screw plug, being threaded at 2 to enter a threaded spark plug opening. The plug is provided with a central passage 3, and is tapered along its bottom, as indicated at 4, for a purpose hereinafter explained.

65 A cylinder 5 is threaded at its lower and at its upper end, the lower end entering a threaded recess in the plug 1, and the upper

end entering a similar threaded recess in a cap 6. The cap 6 is provided with a central threaded opening 7 arranged to receive a screw plug 8. The latter is provided with a head 9 and has an opening 10 which extends through the head and through the body of the screw plug. The head is provided with a recess 11 in which is disposed a tooth or projection 12 which is held by a pin 13 or by any suitable retaining means. On the side of the head opposite the tooth 12 is a bore 14 in which is disposed a spiral spring 15 having a cap 16 at one end, and bearing at the other end on a screw plug 17.

Arranged to pass through the opening 10 is a stem 18 which is provided with numerals 19 to indicate the pressure, preferably in pounds per square inch. One edge of the stem 18 is provided with teeth 20 which are arranged to engage the tooth 12. The lower end of the stem 18 is connected by means of a wrist pin 21 with a plunger head 22. Between the plunger head 22 and the cap 6 is disposed a spiral spring 23. The plunger head 22 has a grooved stop member 24 on its under side.

From the foregoing description of the various parts of the device, the operation thereof may be readily understood. In ascertaining the compression of the engine, the screw plug 1 is inserted in the spark plug opening, and the engine is either turned over by hand or the self starter is started with the ignition switch off. The air under compression will pass through the opening 3, and will force the plunger head 22 upwardly against the tension of the spring 23. As the stem 18 moves upwardly, the teeth on the stem are held in engagement with the tooth 12. The stem will be forced as far as the pressure will warrant. The pressure may be noted from the indicating marks 19, the tooth 12 holding the stem in position. When it is desired to restore the stem to its original position, all that is necessary is to press it toward the right in Figures 1 and 2, compressing the spring 15 and freeing the teeth 20 from the tooth 12. The spring 23 will then return the plunger head to its original position. The underside of the plunger head bears a stop member 24 which is arranged to engage a spider 25 to limit the movement of the plunger head.

When the device is used for measuring the pressure of a pneumatic tire, the valve is

inserted in the opening 3 and pressed inwardly until the valve stem comes in contact with the spider 25, when the valve is forced open and the pressure permitted to act 5 on the plunger head 22, thereby moving the stem 18 to indicate the pressure within the tube.

The tension of the spring 23 may be varied by turning the cap 6. It will be observed 10 that the opening 10 in the screw plug 8 is large enough to give the stem 18 sufficient play to clear the tooth 12 when the stem is moved away from the tooth against the tension of the spring 15. The device is positive 15 in action and is easily operated.

I claim:

1. A combined tire gauge and engine compression gauge comprising a cylindrical casing, an indicating stem slideable into and 20 out of said casing, a spring for normally holding said stem within said casing, a plunger head secured to the stem for moving the latter against the tension of said spring, means for retaining the stem in its 25 shifted position, and a base carried at one end of said casing, said base being adapted to be screwed into a spark plug opening and having a central opening therethrough adapted to receive a tire valve stem.

2. A combined tire and engine compression gauge comprising a cylindrical casing, an indicating stem slideable through one end of said casing, a plunger head pivotally connected with said stem, a spiral spring disposed between said plunger head and one 35 end of said casing, a series of teeth carried by said stem arranged to engage a portion of said casing, spring means for normally

holding said teeth in engagement with said casing, and a circular base carried by the 40 opposite end of said casing, said base having threads disposed on its outer surface adapted to screw into a spark plug opening, and a centrally located opening therethrough adapted to receive a tire valve stem. 45

3. A pressure gauge comprising a cylindrical casing, a base secured to the casing at one end, said base having a central opening, a cap secured to the casing at the opposite end, a screw plug carried by the cap, 50 said screw plug having an opening, an indicating stem arranged to slide through the opening in the screw plug, a plunger head pivotally secured to said stem, a spiral spring disposed between said plunger head 55 and said cap, and means carried by said screw plug and arranged to engage a portion of the plug for holding the stem in its shifted positions.

4. A pressure gauge comprising a cylindrical casing, a base secured to the casing at one end, said base having a central opening, a cap secured to the casing at the opposite end, a screw plug carried by the cap, 60 said screw plug having an opening, an indicating stem arranged to slide through the opening in the screw plug, a plunger head pivotally secured to said stem, a spiral spring disposed between said plunger head and said cap, a pivot carried by the stem on 65 one side thereof, a fixed tooth carried by the screw plug and arranged to be engaged by the tooth on the stem, and spring means for forcing said stem toward said fixed tooth. 70

HARRY ALBERT WALKER.
